UNITED STATES PATENT OFFICE.

LOTHAR R. ZIFFERER, OF COLUMBIA, PENNSYLVANIA.

NUTCRACKER.

Application filed February 15, 1926. Serial No. 88,288.

This invention relates to a nut cracker employing the cam and lever principle for gaining a mechanical advantage whereby to apply a crushing force to a nut which is placed between its jaws.

For its object this invention aims at simplicity, strength, and effective application of a force by which to crush a nut or other object. As illustrative of one embodiment of my invention reference may be had to the accompanying drawing wherein Figs. 1 and 2 are plan views of a nut cracker showing the jaws in two different positions; and Fig. 3 is a transverse section therethrough taken on line 3—3 of Fig. 2.

In the form shown, my device comprises what may be termed a stationary jaw A to which is pivoted at 4 a movable jaw B. As by means of a spring 5 the two jaws are normally held apart in the position of Fig. 1. The engaging faces of the jaw are preferably serrated, and may diverge so as to accommodate nuts of varying size.

At the end of the stationary jaw remote from its pivotal connection 4, I provide a laterally extending slotted arm 6. Within the slotted end of this arm is pivotally connected, as at 7, a second-class lever C which is suitably configured to be grasped by the hand. As part of this lever, I provide a cam 9 preferably slotted as at 10 to receive a rib 11 which extends lengthwise along the movable jaw. The cam engages with the movable jaw close to the free end thereof, and with inward movement of the lever shifts its weight point longitudinally thereof toward the pivotal connection 4.

The shape of the lateral arm 6 conforms generally to the movement curve of the free end of the jaw 6, from which projects a lug 12 which is slidably received within the slot of this arm. By this means the jaw B is guided throughout its movements. In like manner, the rib and slot engagement of this same jaw and lever C tends to hold the one part in correct alignment with the other in all positions of their relative movement. I provide further on the short end of the lever a nose 13 which engages with the lug 12 when the parts are in their normal position, as in Fig. 1, whereby the lever is prevented from swinging outwardly beyond the point indicated.

It is preferred that the outer side of the

stationary jaw should be suitably rounded to enable the operator's fingers to grasp the same comfortably. Upon placing a nut, or other object, between the jaws and applying pressure to the lever, its cam 9 will exert a force against the movable jaw B such as to close the space between the jaws with crushing effect. The cam 9 has a shifting weight point in these lever movements, the fulcrum 7 remaining fixed. The closing movement of the jaws is brought to a stop when the lug 12 engages with the end of the slot in the lateral arm, as indicated in Fig. 2.

A nut cracker constructed in accordance with the description just given is very durable, and capable of exerting a powerful and crushing force against the nut or other object which is positioned between its two jaws. The device need not be handled with any special care since there are no parts to get out of order, and ample provision is made for assuring that the several moving parts shall remain always properly centered. In addition, the movable jaw which takes the thrust from the lever is reinforced longitudinally by the rib, and thus acts to withstand any pressure which may be put upon it without bending or distortion.

I claim:

1. In a nut cracker, the combination of a pair of jaws interpivotally at one end, spring means tending to separate the jaws, an arm extended from the free end of one jaw to overlie the corresponding end of the other jaw, a rib extending longitudinally along the jaw last named, a lever having a slotted arm adapted to straddle the rib and bear against the jaw, and a pivotal connection between the lever and the arm which is extended from the other jaw, substantially as described.

2. In a nut cracker, the combination of a pair of pivoted jaws, one having a slotted arm extended laterally to overlie the other, a lever pivoted to said arm and having a cam in engagement with the other jaw, and a reinforcing rib extending longitudinally along the other jaw, and within a slot which is formed within the cam, the lever being adapted to engage slidably with said jaw whereby to exert a force at shifting points thereupon, substantially as described.

L. R. ZIFFERER.
